UNITED STATES PATENT OFFICE.

EDMOND A. FORDYCE, OF BOSTON, MASSACHUSETTS, ASSIGNOR, BY MESNE ASSIGNMENTS, TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

No. 797,053.

Specification of Letters Patent.

Patented Aug. 15, 1905.

Application filed May 31, 1904. Serial No. 210,831.

To all whom it may concern:

Be it known that I, EDMOND A. FORDYCE, of Boston, in the county of Suffolk and State of Massachusetts, have invented certain new and useful Improvements in Pneumatic-Despatch-Tube Apparatus, of which the following is a specification.

My invention relates to new and useful improvements in terminals for pneumatic-despatch-tube apparatus in which a single line is used for the transmission of carriers in both directions and in which pressure is used behind the carriers to drive them from terminal to terminal.

The main object of my invention is to economize in the air consumption in pneumatic-despatch systems, the air-pressure being used only when the carriers are being transmitted through the tube. This and other objects are accomplished by the mechanism shown and hereinafter described.

My invention consists of certain novel features hereinafter described, and particularly pointed out in the claims.

In the accompanying drawings, which illustrate a construction embodying my invention, Figure 1 is a side elevation of the pneumatic-despatch-tube apparatus, partly broken away to show a carrier traveling from the right-hand terminal to the left-hand terminal. Fig. 2 is a longitudinal sectional view through the terminal, with part of the transmission-tube and pressure-tube in full lines, with the parts of both terminals in normal position and no carrier in transit. Fig. 3 is a similar view to Fig. 2, with the left-hand terminal closed and showing a carrier traveling from the left-hand terminal to the right-hand terminal. Fig. 4 is an interior view of the left-hand terminal, showing the interior construction with parts in their normal positions. Fig. 5 is a top plan view of the left-hand terminal with the cover and sliding valve removed to show the interior mechanism. Fig. 6 is an interior view of the left-hand terminal, showing the interior construction, the parts in position immediately after a carrier has been despatched from the left-hand terminal. Fig. 7 is a cross-sectional view on the line X X, Fig. 6, looking in the direction indicated by the arrow and showing the position of the parts after a carrier has been despatched. Fig. 8 is an un-

der plan view of the slide-valve of each terminal. Fig. 9 is a detail view of the slide-valve with the lever for locking the valve in its closed position. Fig. 10 is a detail view of the mechanism which normally holds the slide-valve at the right-hand terminal in its open position and is identical with the same mechanism at the right-hand terminal. Figs. 11 and 12 are respectively plan and side views of the lever located in the path of the incoming and outgoing carriers at each terminal. Fig. 13 is a detail view, partly in section, of the elastic circuit controller. Fig. 14 is a diagrammatic view illustrating the circuits between the two opposite terminals. Fig. 15 is a sectional detail view hereinafter described. Fig. 16 is a plan view of same.

Like characters of reference refer to like parts throughout the several views.

The transmission-tube A for the carriers receives its pressure from the pressure-tube B, connected by the pipe B' to any suitable source of air-pressure, and said tube B connects with the transmission-tube A at the right-hand and left-hand terminals D D', respectively, as hereinafter described. The upper ends of the tube A are in alignment with the chutes D² D³ of the terminals D D', respectively, which guide the discharging carriers to a suitable receptacle.

With the parts shown in Figs. 2 and 4 a carrier is inserted for despatch into the left-hand terminal D' and passes down into the transmission-tube A and in its travel strikes the lever E, which is connected to the link F' by the pin E⁷ working in the slot F and moves said lever E downward in the slot A², (dotted lines, Fig. 12,) and the motion of this lever E is communicated to the pawl f, which is pivoted at F³ to the link F' and at F⁴ to the piece F⁵, secured to the side of the casing. This downward movement of the link F' pulls the right-hand end of the pawl f away from the front end of the catch F⁶, pivoted to the slide-valve G at F², so that the operator taking hold of the handle G' can move the slide-valve G into its closed position, (shown in Fig. 6,) where it is held closed by the lever G² (shown in Fig. 9) against the tension of the springs H³, which normally tend to open the slide-valve G and hold it in the position shown in Figs. 2 and 4. These springs H³ are connected to pins

H^2 on the under side of the slide-valve G and at the opposite end are secured to a suitable pin in the casing, as shown in Figs. 2, 3, 4, and 6. The upper end G^3 of the lever G^2 engages with the recess G^4 in the under side of the slide-valve G when the slide-valve G is moved into its closed position, (shown in Fig. 9,) and the spring G^5 normally tends to hold the upper end G^3 in the upper position ready to engage the slide-valve G when the same is closed by the operator for the transmission of a carrier. As shown in Fig. 4, the upper end G^3 of the lever G^2 is in contact with the forward end of the slide-valve G when in its open position.

The spring F^7 , as shown in Figs. 4, 6, 9, and 10, tends to hold the front end of the catch F^8 down, so as to normally engage the right-hand end of the pawl f , and when the right-hand end of the pawl f is pulled down by the link F^9 and away from the catch F^8 the pawl F^8 engages the pawl f and holds the same down under the influence of the spring F^9 , secured around the pin F^{10} , until the slide-valve G is moved into its closed position, and in the movement of the slide-valve G to its closed position one of the buffers h^2 on the under side of the rear end of said valve G rides over the upper end of the pawl F^8 and throws its forward end downward, releasing the pawl f , which moves upward to its normal position under the tension of the spring F^9 in position to engage the front end of the catch F^8 when the slide-valve G is returned to its normal open position.

Secured to the under side of the slide-valve G are two lugs H^4 , in which is pivoted the finger H^5 , mounted fast on the shaft H^7 and normally held in its vertical position by the spring H^8 , secured to the pin H^9 on the under side of the slide-valve G , (shown in Fig. 8,) and the lower end of said finger H^5 is provided with an antifriction-roller H^6 . This finger H^5 when moved forward is held firmly in its vertical position by the upper square end h engaging the under side of the slide-valve G , so that in the forward movement of the slide-valve G the roller H^6 moves along the top of the lever J , pivoted at K to the casing of the terminal, and depresses said lever from the position shown in Fig. 4 to that shown in Fig. 6 and passes over and beyond the upper curved end of the lever J , as shown in Fig. 6, moving down the rod K^2 , pivoted thereto, bringing the contact-point K^6 , mounted on the cross-arm K^5 , into contact with the electric contacts $k k'$, and at the same time this downward movement of the lever J opens the valve K^3 , controlling the flow of air-pressure from the supply-pipe B into the terminal to the transmission-tube A . The lower end of the rod K^2 passes through the guide K^4 and carries on its lower end the valve K^3 . This closing of the electric circuit through the contacts $k k'$ energizes the magnets $K' K'$ and act-

ing on the armature J' holds the lever J in its lower position, (shown in Fig. 6,) thereby holding open the valve K^3 until the carrier reaches its destination at the opposite end of the line. The magnets $K' K'$ being energized draw the armature L to its poles, which in turn throws out into the upper end of the tube A the dogs L^4 , located in suitable slots at both ends of the line, which prevents a carrier being despatched from the opposite ends of the line while the carrier is in transit toward that end, as an attempt to insert a carrier would bring it into contact with the upper end of the dog L^4 and prevent such insertion. The armature L is mounted on the bracket L' by the pins $L^2 L^3$, Figs. 5 and 7, a slot being provided around the pins L^2 to allow inward and outward movement of the armature L . The armature L at each terminal is pivotally connected by the link L^5 to the dog L^4 , which is supported on the shaft L^6 and normally held inward by the spring L^7 , connected to said dog, and at its opposite end to the bearing G^6 of the lever G^2 . Beyond the collar L^8 of the dog L^4 on the bearing L^6 is a suitable pin for holding said dog on said bearing. As will hereinafter be shown, when the electric circuit is closed through magnets at one terminal it is closed through the magnets at the other terminal, so that when the armature L at, say, the right-hand station is attracted and throws the dog L^4 out into the upper end of the tube A the same operation takes place at the left-hand terminal, and vice versa, as the armature L being attracted by the magnets at that terminal forces the dog L^4 of that terminal out into the upper end of the tube A at the left-hand terminal into the path of the traveling carrier moving from the right to the left hand terminal. In respect to the operation of the dogs L^4 at each end of the line the mechanism is identical and the operation is the same at both terminals, so that when a carrier is despatched from either end to the other the dogs L^4 are thrown out into the upper ends of the transmission-tube A —that is, moving from the inner position (shown in Fig. 4) to the outer position (shown in Fig. 6).

With the slide-valve G of the left-hand terminal closed and the parts in the position shown in Figs. 3 and 6 and the pin A^6 between the electric contacts $k k'$ the current will flow from the battery C through the wire 1, to the binding-post c , to the magnet K' in the left-hand terminal, holding down the armature J' , which causes the opening of the valve K^3 . Then the current passes through the wire a , through the electric contacts $k k'$, hence through the wire 17 to the binding-post 9, to the wire 8, to the binding-post 7, to the wire 6, through the electric contacts $e e'$ and the circuit-controller E^9 , then through the wire 5 to the electric contact k' , through the wire 4 to the magnet K' , which excites the magnet in the

right-hand end of the terminal, so that in both terminals the armature L is drawn to the poles of both magnets, thus throwing out the dogs L⁴ in both terminals. Then the current passes through the magnet K' to the binding-post 3, hence to the wire 2, to the battery C.

Now with the parts in the position previously described the carrier A' (shown in Fig. 3) is traveling from the left-hand terminal toward the right-hand terminal and upon reaching the right-hand terminal in passing up strikes the lever E in the slot A². This lever E is pivotally connected by the pin E' to the extended arms E³ of the rocker-arm E³, which is pinned fast on the shaft E⁴ by means of the set-screw E¹² and has bearings in the lugs E⁵. On the outer end of the shaft E⁴ is secured the non-conductive fiber roller E¹⁰, secured fast to the shaft E⁴ by the pin E⁹ in the inner portion E⁸, and in said roller E¹⁰ there is located the metallic strip E¹⁴, which extends through from side to side, as shown. Normally the metallic strip E¹⁴ bears against the electric contacts e e', mounted on suitable insulating material e², securely mounted in the base of the terminal. The inner end of the spring E¹¹ is connected to the roller E¹⁰ and the other extends into one of the lugs E⁵, and the object of said spring is to keep the rocker-arm E³ in the position shown in full lines, Fig. 12. Around the pin E' is a spring E¹⁵, one end of which extends beyond the rocker-arm E³ and the other extends beyond the lever E, as shown in dotted lines, Fig. 11, and said spring normally holds said lever in the position shown in full lines, Fig. 4, and in the path of the incoming and outgoing carrier. The inner forked ends E² of the lever E are squared up on their upper ends, as shown in Fig. 12, so that a carrier inserted strikes the lever E, which swings, as shown in lower dotted lines, Fig. 12, and allows the carrier to continue its travel without affecting the rocker-arm E³, while an outgoing carrier coming from, say, the left-hand to the right-hand terminal will strike the lever E and rotate said lever and rocker-arm E³ in the position shown in upper dotted lines, Fig. 12, because the square end E² bears against said rocker-arm and causes it to move with the lever E. The rotation of the rocker-arm E³ causes the rotation of the roller E¹⁰, and said roller is secured fast to the shaft E⁴, on which the rocker-arm E³ is also fast. This rotation of the roller E¹⁰ causes the metallic strip E¹⁴ to move from the contacts e e' and when the electric circuit is closed causes the same to be broken.

Now the carrier A', previously mentioned, moving from the left to the right hand terminal when it reaches the right-hand terminal will strike the lever E and cause the roller E¹⁰ to rotate (owing to the connections previously described) and break the electric circuit at the contacts e e', which will deener-

gize the magnets K', thus releasing the armatures L, and the dogs L⁴ at both terminals will be drawn back into their inner position by the springs L⁷. At the same time the spring M, bearing against the under side of the arm K⁵, and guide M' will move the the rod K², closing the valve K³, and in the upward movement of the rod K² the arm J², Fig. 5, will strike the lever G², raising the rear end of said lever upward against the spring G⁵, pulling down the front end G³ from its engagement with the slide-valve G, thereby releasing the valve, which is thrown into its open position by the springs H³, and as said slide-valve comes to its inner open position the catch F⁶ engages the front end of the pawl f, and said slide-valve is thus held securely in its open position ready for the insertion of another carrier into the terminal and cannot be closed until a carrier is inserted into the tube.

The front end d of the slide-valve G passes beyond the point d' of the plate H before the roller H⁶ strikes the upper curved portion of the lever J to bring it down into proximity with the magnets K' and cause the closing of the electric circuit in the valve K³, so that the objectionable hissing sound of the air entering the terminal from the supply-pipe B is not heard.

On the lower end of the bracket F⁶ is located the arm N, with a suitable rubber buffer, against which the lever E in its vertical movement cushions.

The construction and operation of the above terminals are exactly the same. If a carrier is inserted into the right-hand terminal, the course of the electric circuit is as follows: Starting at the battery C the current passes through the wire 2 to the binding-post 3, hence to the magnet K', which operates exactly the same as the magnet K' previously described for the left-hand terminal, then through the wire 4 to the electric contacts k k', through the wire 16 to the binding-post 15 and wire 14, to the binding-post 13, to the wire 12, to the contacts e e', to the controller E¹⁰, to the contact e, through the wire 10 to the contact T, through the wire a to the magnet K', which attracts the armature L and throws the dog L⁴ out at the left-hand terminal in the manner previously described. Hence the current passes to the binding-post c, to the wire 1, to the battery C.

Having thus described the nature of my invention and set forth a construction embodying the same, what I claim as new, and desire to secure by Letters Patent of the United States, is—

1. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed

air, an air-inlet from said source of compressed air to the transmission-tube, a valve controlling said air-inlet, means for normally holding said air-inlet valve closed, and mechanism operated by the closing of said carrier-inlet valve for opening said air-inlet valve.

2. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, means for holding said air-inlet valve open, and means at the opposite end of the transmission-tube in the line of travel of the traveling carriers and adapted to be operated thereby to release said air-inlet-holding means to allow said air-inlet valve to close.

3. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, means for holding said air-inlet valve open, and means at the opposite end of the transmission-tube for releasing said air-inlet-holding means to allow said air-inlet valve to close upon the discharge of carriers at the opposite end of the line.

4. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, and mechanism operated by the closing of said carrier-inlet valve after its said release for opening said air-inlet valve.

5. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the trans-

mission-tube, a valve controlling said air-inlet, means for normally holding said air-inlet valve closed, mechanism operated by the closing of said carrier-inlet valve after its said release for opening said air-inlet valve, means for holding said air-inlet valve open, and means at the opposite end of the transmission-tube in the line of travel of the traveling carriers and adapted to be operated thereby to release said air-inlet-holding means to allow said air-inlet valve to close.

6. In a pneumatic-despatch-tube apparatus, a carrier-transmission tube having an inlet and an outlet for the carriers, a valve for closing said inlet after the insertion of the carriers, a locking device for normally holding said carrier-inlet valve open, and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, means for holding said air-inlet valve open, and means at the opposite end of the transmission-tube for releasing said air-inlet-holding means to allow said air-inlet valve to close upon the discharge of carriers at the opposite end of the line.

7. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, and mechanism operated by the closing of said carrier-inlet valve after its said release for opening said air-inlet valve.

8. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said

air-inlet valve, means for holding said air-inlet valve open, and means at the opposite end of the transmission-tube in the line of traveling carriers and adapted to be operated thereby to release said air-inlet-holding means to allow said air-inlet valve to close.

9. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, means for holding said air-inlet valve open, and means at the opposite end of the transmission-tube for releasing said air-inlet-holding means to allow said air-inlet valve to close upon the discharge of carriers at the opposite end of the line.

10. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, a lock for holding said carrier-inlet valve closed, mechanism operated upon the closing of said air-inlet valve for releasing said lock, and means for returning said carrier-inlet valve to its normal open position.

11. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, means for holding said air-inlet valve open, means at the opposite end of the transmission-tube in the line of travel of the traveling carriers and adapted to be operated thereby to release said air-inlet-holding means to allow said air-inlet valve to close, a lock for holding said carrier-inlet valve closed, mechanism operated upon the closing of said air-inlet valve for releasing said lock,

and means for returning said carrier-inlet valve to its normal open position.

12. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, means for holding said air-inlet valve open, means at the opposite end of the transmission-tube for releasing said air-inlet-holding means to allow said air-inlet valve to close upon the discharge of carriers at the opposite end of the line, a lock for holding said carrier-inlet valve closed, mechanism operated upon the closing of said air-inlet valve for releasing said lock, and means for returning said carrier-inlet valve to its normal open position.

13. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, a lock for holding said carrier-inlet valve closed, mechanism operated upon the closing of said air-inlet valve for releasing said lock, and means for returning said carrier-inlet valve to its normal open position.

14. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, means for holding said air-inlet valve open, means at the opposite end of the transmission-tube in the line of travel of the traveling carriers and adapted to be operated thereby to release said air-inlet-holding means to allow said air-inlet valve to close, a lock for holding said carrier-inlet valve closed, mechanism operated upon the closing of said air-inlet valve for

releasing said lock, and means for returning said carrier-inlet valve to its normal open position.

15. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, means for holding said air-inlet valve open, means at the opposite end of the transmission-tube for releasing said air-inlet-holding means to allow said air-inlet valve to close upon the discharge of carriers at the opposite end of the line, a lock for holding said carrier-inlet valve closed, mechanism operated upon the closing of said air-inlet valve for releasing said lock, and means for returning said carrier-inlet valve to its normal open position.

16. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, a lock for holding said carrier-inlet valve closed, mechanism operated upon the closing of said air-inlet valve for releasing said lock, and means for returning said carrier-inlet valve to its normal open position.

17. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its

said release for opening said air-inlet valve, means for holding said air-inlet valve open, means at the opposite end of the transmission-tube in the line of the traveling carriers and adapted to be operated thereby to release said air-inlet-holding means to allow said air-inlet valve to close, a lock for holding said carrier-inlet valve closed, mechanism operated upon the closing of said air-inlet valve for releasing said lock, and means for returning said carrier-inlet valve to its normal open position.

18. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, means for holding said air-inlet valve open, means at the opposite end of the transmission-tube for releasing said air-inlet-holding means to allow said air-inlet valve to close upon the discharge of carriers at the opposite end of the line, a lock for holding said carrier-inlet valve closed, mechanism operated upon the closing of said air-inlet valve for releasing said lock, and means for returning said carrier-inlet valve to its normal open position.

19. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, means for holding said air-inlet valve open, means at the opposite end of the transmission-tube in the line of the traveling carriers and adapted to be operated thereby to release said air-inlet-holding means to allow said air-inlet valve to close, a locking-lever for holding said carrier-inlet valve closed, a spring for holding said locking-lever in engagement with said carrier-inlet valve in its closed position, mechanism operated upon the closing

of said air-inlet valve for releasing said locking-lever, and springs for returning said carrier-inlet valve to its normal open position.

20. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, means for holding said air-inlet valve open, means at the opposite end of the transmission-tube for releasing said air-inlet-holding means to allow said air-inlet valve to close upon the discharge of carriers at the opposite end of the line, a locking-lever for holding said carrier-inlet valve closed, a spring for holding said locking-lever in engagement with said carrier-inlet valve in its closed position, mechanism operated upon the closing of said air-inlet valve for releasing said locking-lever, and springs for returning said carrier-inlet valve in its normal open position.

21. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, means for holding said air-inlet valve open, means at the opposite end of the transmission-tube in the line of travel of the traveling carriers and adapted to be operated thereby to release said air-inlet-holding means to allow said air-inlet valve to close, and a device normally out of the line of travel of the traveling carrier and adapted to be moved into said line of travel to prevent the insertion of a carrier at one end of the transmission-tube when a carrier is in transit from the opposite end of said transmission-tube.

22. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a

valve controlling said air-inlet, means for normally holding said air-inlet valve closed, mechanism operated by the closing of said carrier-inlet valve for opening said air-inlet valve, means for holding said air-inlet valve open, means at the opposite end of the transmission-tube for releasing said air-inlet-holding means to allow said air-inlet valve to close upon the discharge of carriers at the opposite end of the line, and a device normally out of the line of travel of the traveling carrier and adapted to be moved into said line of travel to prevent the insertion of a carrier at one end of the transmission-tube when a carrier is in transit from the opposite end of said transmission-tube. *

23. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, means for holding said air-inlet valve open, means at the opposite end of the transmission-tube in the line of travel of the traveling carriers and adapted to be operated thereby to release said air-inlet-holding means to allow said air-inlet valve to close, and a device normally out of the line of travel of the traveling carrier and adapted to be moved into said line of travel to prevent the insertion of a carrier at one end of the transmission-tube when a carrier is in transit from the opposite end of said transmission-tube.

24. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, means for holding said air-inlet valve open, means at the opposite end of the transmission-tube for releasing said air-inlet-holding means to allow said air-inlet valve to close upon the discharge of carriers at the opposite end of the line, and a device normally out of the line of travel of the traveling carrier and adapted to be moved into said line of travel to prevent the insertion of a carrier at one end of the transmission-

tube when a carrier is in transit from the opposite end of said transmission-tube.

25. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, means for holding said air-inlet valve open, means at the opposite end of the transmission-tube in the line of the traveling carriers and adapted to be operated thereby to release said air-inlet-holding means to allow said air-inlet valve to close, a lock for holding said carrier-inlet valve closed, mechanism operated upon the closing of said air-inlet valve for releasing said lock, means for returning said carrier-inlet valve to its normal open position, and a device normally out of the line of travel of the traveling carrier and adapted to be moved into said line of travel to prevent the insertion of a carrier at one end of the transmission-tube when a carrier is in transit from the opposite end of said transmission-tube.

26. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, means for holding said air-inlet valve open, means at the opposite end of the transmission-tube for releasing said air-inlet-holding means to allow said air-inlet valve to close upon the discharge of carriers at the opposite end of the line, a lock for holding said carrier-inlet valve closed, mechanism operated upon the closing of said air-inlet valve for releasing said lock, means for returning said carrier-inlet valve to its normal open position, and a device normally out of the line of travel of the traveling carriers and adapted to be moved into said line of travel to prevent the insertion of a carrier at one end of the transmission-tube when a carrier is in transit from the opposite end of the transmission-tube.

27. In a pneumatic-despatch-tube apparatus, a carrier-transmission tube having an inlet and an outlet for the carriers, a valve for closing said inlet after the insertion of the carriers, a locking device for normally holding

said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, means for holding said air-inlet valve open, means at the opposite end of the transmission-tube in the line of travel of the traveling carriers and adapted to be operated thereby to release said air-inlet-holding means to allow said air-inlet valve to close, a lock for holding said carrier-inlet valve closed, mechanism operated upon the closing of said air-inlet valve for releasing said lock, means for returning said carrier-inlet valve to its normal open position, and a device normally out of the line of travel of the traveling carrier and adapted to be moved into said line of travel to prevent the insertion of a carrier at one end of the transmission-tube when a carrier is in transit from the opposite end of said transmission-tube.

28. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, means for holding said air-inlet valve open, means at the opposite end of the transmission-tube for releasing said air-inlet-holding means to allow said air-inlet valve to close upon the discharge of carriers at the opposite end of the line, a lock for holding said carrier-inlet valve closed, mechanism operated upon the closing of said air-inlet valve for releasing said lock, means for returning said carrier-inlet valve to its normal open position, and a device normally out of the line of travel of the traveling carriers and adapted to be moved into said line of travel to prevent the insertion of a carrier at one end of the transmission-tube when a carrier is in transit from the opposite end of said transmission-tube.

29. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling

said air-inlet, means for normally holding said air-inlet valve closed, mechanism operated by the closing of said carrier-inlet valve after its said release for opening said air-inlet valve, means for holding said air-inlet valve open, means at the opposite end of the transmission-tube in the line of the traveling carriers and adapted to be operated thereby to release said air-inlet-holding means to allow said air-inlet valve to close, a lock for holding said carrier-inlet valve closed, mechanism operated upon the closing of said air-inlet valve for releasing said lock, means for returning said carrier-inlet valve to its normal open position, and a device normally out of the line of travel of the traveling carriers and adapted to be moved into said line of travel to prevent the insertion of a carrier at one end of the transmission-tube when a carrier is in transit from the opposite end of said transmission-tube.

30. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, means for holding said air-inlet valve open, means at the opposite end of the transmission-tube for releasing said air-inlet-holding means to allow said air-inlet valve to close upon the discharge of carriers at the opposite end of the line, a lock for holding said carrier-inlet valve closed, mechanism operated upon the closing of said air-inlet valve for releasing said lock, means for returning said carrier-inlet valve to its normal open position, and a device normally out of the line of travel of the traveling carrier and adapted to be moved into said line of travel to prevent the insertion of a carrier at one end of the transmission-tube when a carrier is in transit from the opposite end of said transmission-tube.

31. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the

closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, and circuit-breaking means located at the opposite end of the transmission-tube and in the line of the traveling carriers and adapted to be operated upon the discharge of a carrier to break the electric circuit and release said air-inlet-holding means at the despatch end of the transmission-tube to allow the air-inlet valve to close.

32. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, and circuit-breaking means located at the opposite end of the transmission-tube and in the line of traveling carriers and adapted to be operated upon the discharge of a carrier to break said circuit and release said air-inlet-holding means at the despatch end of the transmission-tube to allow the air-inlet valve to close.

33. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for

opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, and circuit-breaking means located at the opposite end of the transmission-tube and in the line of the traveling carriers and adapted to be operated upon the discharge of a carrier to break said circuit and release said air-inlet-holding means at the opposite end of the transmission-tube to allow the air-inlet valve to close.

34. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carrier and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, and means for returning said carrier-inlet valve to its normal open position.

35. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of

the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, and means for returning said carrier-inlet valve to its normal open position.

36. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, and means for returning said carrier-inlet valve to its normal open position.

37. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit and

energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, and means for returning said carrier-inlet valve to its normal open position.

38. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, and means for returning said carrier-inlet valve to its normal open position.

39. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve,

an electric circuit, circuit - closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier - inlet valve closed, mechanism operated upon the closing of said air - inlet valve for releasing said lock, and means for returning said carrier-inlet valve to its normal open position.

40. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

41. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break the electric circuit and release said air-inlet-holding means at the despatch end of the transmission-tube to allow the air-inlet valve to close, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

42. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit, and energized upon the closing of said circuit by the closing of the carrier-inlet valve to hold said air-inlet valve open, circuit-breaking means located at the opposite end of the transmission-tube and in the line of traveling carriers and adapted to be operated upon the discharge of a carrier to break said circuit and release said air-inlet-holding means at the opposite end of the transmission-tube to allow the air-inlet valve to close, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

43. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

44. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, an electric circuit, circuit-closing means adapt-

ed to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

45. In a pneumatic-despatch-tube apparatus, a carrier-transmission tube having an inlet and an outlet for the carriers, a valve for closing said inlet after the insertion of the carriers, a locking device for normally holding said carrier-inlet valve open, a source of compressed air, an air-inlet from said source of compressed air to the transmission-tube, a valve controlling said air-inlet, means for normally holding said air-inlet valve closed, mechanism operated by the closing of said carrier-inlet valve for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of traveling carriers and adapted upon the closing of the electric circuit to move into said line of travel and prevent the insertion of a carrier at the end of the line opposite to that from which the carrier was despatched and to return to its normal position when the circuit is broken.

46. In a pneumatic-despatch-tube apparatus, a carrier-transmission tube and having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of traveling carriers and adapted upon the closing of the electric circuit to move into said line of travel and prevent the insertion of a carrier at the end of the line opposite to that from which the carrier was despatched and to return to its normal position when the circuit is broken.

47. In a pneumatic-despatch-tube apparatus, a carrier-transmission tube having an inlet and an outlet for the carriers, a valve for closing said inlet after the insertion of the carriers, a locking device for normally holding said carrier-inlet valve open and operated by an inserted carrier to release said carrier-inlet valve, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of traveling carriers and adapted upon the closing of the electric circuit to move into said line of travel and prevent the insertion of a carrier at the end of the line opposite to that from which the carrier was despatched and to return to its normal position when the circuit is broken.

the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

48. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

49. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating

said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its said release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

50. In a pneumatic-despatch-tube apparatus, a carrier-transmission tube having an inlet and an outlet for the carriers, a valve for closing said inlet after the insertion of the carriers, a locking device for normally holding said carrier-inlet valve open, mechanism operated by an inserted carrier for operating said locking device to release said carrier-inlet valve, means for holding said locking device in its released position until the carrier-inlet valve is closed, a source of compressed air, an air-inlet from said source of compressed air to the transmission-tube, a valve controlling said air-inlet, means for normally holding said air-inlet valve closed, mechanism operated by the closing of said carrier-inlet valve after its release for opening said air-inlet valve, an electric circuit, circuit-closing means adapted to be operated upon the closing of the carrier-inlet valve at one end of the transmission-tube to close the circuit, an electromagnet included in said circuit and energized upon the closing of said circuit by the closing of the carrier-inlet valve to hold said air-inlet valve open, circuit-breaking means located at the opposite end of the transmission-tube and in the line of the traveling carriers and adapted to be operated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of the traveling carriers and adapted upon the closing of the electric circuit to move into said line of travel and prevent the insertion of a carrier at the end of the line opposite to that from which the carrier was despatched and to return to its normal position when the circuit is broken.

ated upon the discharge of a carrier to break said circuit and release said air-inlet-holding means at the despatch end of the transmission-tube to allow the air-inlet valve to close, a lock for holding said carrier-inlet valve closed, mechanism operated upon the closing of said air-inlet valve for releasing said lock, means for returning said carrier-inlet valve to its normal open position, and a device located at each end of the transmission-tube and normally out of the line of the traveling carriers and adapted upon the closing of the electric circuit to move into said line of travel and

prevent the insertion of a carrier at the end of the line opposite to that from which the carrier was despatched and to return to its normal position when the circuit is broken.

In testimony whereof I have signed my name to this specification, in the presence of two subscribing witnesses, this 25th day of May, A. D. 1904.

EDMOND A. FORDYCE.
